US0D1095234S

(12) **United States Design Patent** (10) Patent No.: **US D1,095,234 S**
(45) Date of Patent: ** Sep. 30, 2025

(54) **BOTTOM DISPENSING CONTAINER**

(71) Applicant: **The Procter & Gamble Company**,
Cincinnati, OH (US)

(72) Inventors: **Pieter Paul Dirk Jenny Maria Van Den Bergh**, Martens Latem (BE);
Vincent Hubert Monique De Wilde, Holsbeek (BE); **David James McNeill**, London (GB)

(73) Assignee: **The Procter & Gamble Company**,
Cincinnati, OH (US)

(**) Term: **15 Years**

(21) Appl. No.: **29/972,059**

(22) Filed: **Nov. 7, 2024**

Related U.S. Application Data

(60) Continuation of application No. 29/915,988, filed on Nov. 7, 2023, which is a division of application No. 29/810,378, filed on Oct. 5, 2021, now Pat. No. Des. 1,007,319, which is a continuation of application No. 29/765,021, filed on Jan. 5, 2021, now Pat. No. Des. 934,689, which is a division of application No. (Continued)

(57) **CLAIM**

The ornamental design for a bottom dispensing container, as shown and described.

DESCRIPTION

FIG. 1 is a perspective view of a bottom dispensing container;

FIG. 2 is a front view thereof;

FIG. 3 is a right-side view thereof;

FIG. 4 is a rear view thereof;

FIG. 5 is a left-side view thereof;

FIG. 6 is a top view thereof; and,

FIG. 7 is a bottom view thereof.

The broken lines illustrate structure or features that form no part of the claimed design. The (dot-dash or dot-dot-dash) broken line(s) define the bounds of the claimed design and form no part thereof.

1 Claim, 3 Drawing Sheets
